UNITED STATES PATENT OFFICE

GEORGE BASIL KING, OF EDGBASTON, BIRMINGHAM, ENGLAND

GRAMOPHONE

Application filed April 8, 1929, Serial No. 353,544, and in Great Britain November 20, 1928.

This invention relates to gramophones and refers more particularly to the arrangement of the sound box or reproducer by which expression we include electrical sound reproducing appliances, usually known as "pick-ups", and the stylus bar and needle holding device associated therewith.

It is at present the common practice to mount the stylus bar pivotally in relation to the reproducer, the axis of the needle holder, the pivoting point of the stylus bar and the plane of the diaphragm commonly being substantially in alignment. This arrangement does not lend itself conveniently to automatic needle changing unless the fresh needles are fed into the needle holder from the same end as that from which they project when working.

The primary object of the present invention is to introduce certain improvements in the arrangement which will allow of the fresh needles being fed into the needle holder from the opposite end thereof to that from which they project when working and to enable this to be done without affecting the acoustic properties of the reproduction and in the case of a sound box without stressing the diaphragm in any direction except along or parallel to its axis, i. e. the line passing through its centre point and at right angles to the plane containing its periphery.

It is possible to devise an arrangement whereby the needles can be fed into the needle holder at the opposite end therewith from which they are to project when working by off-setting the sound box or reproducer, and such an arrangement has already been proposed but in this arrangement the movements imparted to the needle by the record are not accurately reproduced at the reproducer end of the stylus bar, such movements not being confined to a direction along the axis of the diaphragm or at right angles to the plane of the air gap between the armature associated with the stylus bar, and the electromagnet in the case of an electrical reproducer.

According to the present invention I provide a reproducer having a diaphragm or electro-magnetic system, a stylus bar having a pivotal or equivalent movement, an open

ended passage extending through that part of the stylus bar which serves as a needle holder and a clearance above the needle holder so that the needles can be fed in at the end opposite to that from which their points project when working, the axis of said passage, and a plane at right angles to the axis of the diaphragm passing through the point of contact between the diaphragm and the stylus bar, or the plane of the air gap in the case of the electrical reproducer, both intersecting the axis about which the stylus bar pivots or both pass very closely adjacent thereto.

A further feature of the present invention is to arrange that part of the stylus bar which extends from the pivot or its equivalent to the reproducer angularly in relation to the axis of the needle holding portion of the stylus bar.

The part of the stylus bar extending from the pivoting axis to the reproducer may for instance be disposed at a very considerable angle in relation to the axis of the needle holding portion of the stylus bar.

A further feature of the present invention is to construct that part of the stylus bar which extends from a point adjacent the pivoting axis to the reproducer in such manner that it has a resistance to bending which is accurately proportioned to the bending moment of the stylus bar at every point between the pivot and the end adjacent the reproducer diaphragm or armature to provide the correct degree of elasticity required by the acoustic design and to construct said portion so that the needles may pass therethrough and to provide when necessary means for guiding the needles when passing therethrough into the needle holding portion.

The stylus bar may for instance be formed so that that part which extends from the reproducer to the pivoting axis is of channel section with the back of the channel adjacent to the reproducer.

The guiding means for the needle when passing through the stylus bar may be provided by a blade like extension to one side of the channel which may be bent up whole at right angles to the channel side or it may be

attached so as to form a fourth side of the channel for part of its length. The said blade like extension or portion may have a part which is not rigidly fastened to the channel side but which is bent so as to form the guiding means. Further guiding means may be provided by a tongue pressed out of the back of the channel.

The pivot or its equivalent about which the stylus bar can oscillate may be adjacent to the entrance end of the needle holding portion and the portion extending from the reproducer to the needle holding portion may be connected to the latter intermediate its ends.

Referring to the drawings:—

Figure 1 is a view in side elevation showing one form of sound box constructed in accordance with this invention.

Figure 2 is a plan view.

Figure 3 is a front view.

Figure 4 is a sectional side view on line 4—4 of Figure 3 showing a needle in position.

Figure 5 is a section on line 5—5 Figure 1 showing the needle holder.

Figure 6 is a section on line 6—6 of Figure 5.

Figure 7 is a sectional side view showing another form of the invention.

Figure 8 is a plan view of the construction shown in Figure 7 but with the cover removed.

Figure 9 is a perspective view showing the stylus bar.

Figure 10 is a sectional side view showing the invention applied to an electric reproducer.

Figure 11 is a side view of the apparatus shown in Figure 10 with the cover removed.

Figure 12 is a section on line 12—12 of Figure 10.

Figure 13 is a sectional view in side elevation showing another form of the invention.

Figure 14 is a view showing a blank from which a part of the stylus bar shown in Figure 13 is made.

Figure 15 is a sectional view in side elevation showing another form of the invention.

In the construction shown in Figures 1 to 6 the invention is shown applied to an ordinary sound box having a diaphragm 1 mounted in a casing 2 the casing having a tone arm such as 3.

In this construction, the casing is provided with a pair of projections 4 each having a screw 5 the ends 6 of the screw forming trunnions for the stylus bar.

The stylus bar has a needle holding portion 7 and an arm 8 which extends from the needle holding portion to the diaphragm 1.

The needle holding portion is provided with a longitudinal passage 9 which is open at both ends and the entrance end 10 for needles may be flared or enlarged as shown.

The needle holding portion adjacent the entrance end is provided with a pair of oppositely arranged projections 11 which are recessed at 12 each recess containing a ball 13 which is engaged by the end 6 of one of the screws 5.

Thus the stylus bar as a whole is pivoted about the common axis of the screws 5.

The arm 8 connects with the needle holding portion 7 intermediate the ends of the needle holding portion as shown clearly in Figure 4 and the end of the arm 8 is bent at right angles or substantially so and attached to the centre of the diaphragm 1.

It will be observed that the axis of the needle holding portion 7 passes through the axis of the screws 5 which forms the pivoting axis of the stylus bar and further a plane extending through the point of contact between the arm 8 and the diaphragm 1 and arranged at right angles to the axis of the diaphragm also intersects the axis of the screws 5.

With this arrangement, the vibratory motions of the needle under the influence of the record are faithfully and accurately reproduced at the diaphragm, the movements imparted to the diaphragm by the end of the arm 8 being parallel to the axis of the diaphragm.

A needle magazine is illustrated at 52, this magazine being fixed above and adjacent to the needle holder 7 and having an outlet in line with the bore 9 in the needle holder through which outlet needles are adapted to be ejected one by one into said needle holder, the ejecting means however forming no part of the present invention.

Means are shown whereby the needle 14 may be releasably held in the opening 9 but such means form no part of the present invention.

In Figures 7, 8 and 9, the invention is shown applied to another form of sound box having a diaphragm 15 which is of accurate form and which carries a centre piece 16 which is offset from the plane of the main part of the diaphragm.

The sound box 17 is provided with a short tone arm 18 which is able to rotate about the axis of the arm 19 rotary movement, however, being limited by a pin 20 carried by the arm 19 and working in a slot 21 in the arm 18.

This movement is provided to enable the needle to be moved into a vertical position, the rotation of the arm 18 being about an axis which is at right angles to the plane containing the axis of the needle gripper.

In this case the sound box 17 is provided with a pair of spaced projections 22 which carry the pins 5 which are similar in all respects with the pins 5 described with reference to Figures 1 to 6.

In this construction the needle holding portion 7 of the stylus bar may be formed

substantially as described with reference to Figures 1 to 6 and may be provided with lateral projections 11 which are engaged by the ends of the screws 5 the pivoting point being shown at 23 in Figure 7.

The other part of the stylus bar, however, is of channel form, the channel having a back portion 24 which may be perforated for the sake of lightness and having two flanges 25 the back 24 of the channel being disposed towards the sound box.

At its end the stylus bar is provided with two integral projections 26 which are attached to the portion 16 of the diaphragm.

In Figure 7 the needle magazine 52 from which needles are adapted to be ejected into the needle holder 7 is only shown diagrammatically and forms no part of the present invention.

In this construction the arm 24, 25, 26, is designed so that its moment of resistance to bending is accurately proportioned to the bending moment at every point along its length to give the desired degree of elasticity which is required for perfect reproduction in certain constructions and the weight is kept within the limits required by the acoustic design.

Further, a plane at right angles to the axis of the diaphragm and passing through the point of contact of the parts 26 and 16 intersects the pivot axis 23 and also the axis of the needle holding portion 7 and also intersects the axis 23 so that the movements imparted to the diaphragm or vibrations of the needle are in a direction parallel to the axis of the diaphragm.

In Figures 10, 11 and 12, a construction is shown in which our invention is applied to an electrical reproducer including a coil 27 having a core 28 the stylus bar portion 29 forming the moving armature. The stylus bar portion 30 is provided with a longitudinal passage 31 for receiving the needle, this passage being open at both ends and being enlarged at the end 32 into which the needles are fed.

In this case, the stylus bar is pivoted on a knife edge 33 which is fixed on the reproducer body 34 one end of the part 29 having a clearance hole 35 which engages over a pin 36 a spring 37 being placed under this end of the stylus bar and a nut 38 being placed on the other side of this end of the stylus bar.

Adjacent the pivot point, the stylus bar part 29 is provided with lateral extensions 37 which are attached by means of screws 50 to the reproducer body, these screws, however, passing through clearance holes so that the arm 29 can oscillate on the knife edge 33.

The part 30 of the stylus which holds the needle is provided with a device 39 for holding the needle which device, however, forms no part of the present invention.

It will be observed that in this arrange-

ment the axis of the needle holding part passes through the knife edge 33 and also the plane of the air gap between the arm 29 and the core 28 at right angles to the axis of the coil 27 or at right angles to a plane containing the axes of the two coils 27 (see Figure 12) also passes through the knife edge 33.

In the construction shown in Figures 13 and 14 that part of the stylus bar which extends from the diaphragm or reproducer to the needle holder is made from a blank 40 having ears 41 which are bent backwardly and attached to the diaphragm, the blank being folded along the dotted lines 42 into channel form. The back of the channel is disposed towards the diaphragm and a partially severed tongue of metal 43 is provided which may be bent inwardly as shown at 43 in Figure 13 to guide the needle into the upper end of the needle holder.

Projecting from one edge the blank 40 has a blade like projection 44 which is bent about the dotted line 45 to form the guide 46 to direct the needle into the needle holder.

In order to get the needles into the receiving end of the stylus bar the cover 47 of the sound box may be provided with a tubular guide 48 having a projecting finger 49.

A somewhat similar construction is shown in Figure 15 but in this case the stylus bar portion 50 is of tubular form instead of being of channel form and is provided with guides 46 and 43 similar to those shown in Figure 13.

In this case the cover 47 of the sound box is provided with a tapering tubular guide 51.

What I claim then is:

1. In a gramophone the combination of a reproducer, a stylus bar mounted for vibratory movement, said stylus bar having a needle holding portion, and a reproducer actuating portion, said portions being disposed in out of line relationship, the needle holding portion having an open ended hole extending therethrough, a needle magazine mounted above and adjacent to said needle holder, said magazine having an outlet in line with the hole in said needle holder whereby needles can be fed in from the end opposite to that from which they project when functioning, the axis of said hole, and a plane at right angles to the mean axis of the reproducer through the point of contact between the reproducer and the stylus bar, both substantially intersecting the axis about which the stylus bar vibrates.

2. In a gramophone the combination of a reproducer, a stylus bar mounted for vibratory movement, said stylus bar having a needle holding portion, and a reproducer actuating portion, said portions being disposed in angular relationship, the needle holding portion having an open ended hole extending therethrough, a needle magazine

mounted above and adjacent to said needle holder, said magazine having an outlet in line with the hole in said needle holder whereby needles can be fed in from the end opposite to that from which they project when functioning, the axis of said hole, and a plane at right angles to the mean axis of the reproducer through the point of contact between the reproducer and the stylus bar, both substantially intersecting the axis about which the stylus bar vibrates.

3. In a gramophone the combination of a reproducer, a stylus bar mounted for vibratory movement, said stylus bar having a needle holding portion, and a reproducer actuating portion, said actuating portion being of channel section with the back of the channel disposed towards the reproducer, said portions being disposed in out of line relationship, the needle holding portion having an open ended hole extending therethrough, a needle magazine mounted above and adjacent to said needle holder, said magazine having an outlet in line with the hole in said needle holder whereby needles can be fed in from the end opposite to that from which they project when functioning.

4. In a gramophone the combination of a reproducer, a stylus bar mounted for vibratory movement, said stylus bar having a needle holding portion, and a reproducer actuating portion, said actuating portion being of channel section with the back of the channel disposed towards the reproducer, said portions being disposed in angular relationship, the needle holding portion having an open ended hole extending therethrough, a needle magazine mounted above and adjacent to said needle holder, said magazine having an outlet in line with the hole in said needle holder whereby needles can be fed in from the end opposite to that from which they project when functioning the axis of the hole in said needle holder and a plane at right angles to the mean axis of the reproducer, through the point of contact between the reproducer and the stylus bar, both substantially intersecting the axis about which the stylus bar vibrates.

5. In a gramophone the combination of a reproducer, a stylus bar mounted for vibratory movement, said stylus bar having a needle holding portion, and a reproducer actuating portion, said actuating portion having a longitudinal passage, and a guide for directing the needle into the needle holding portion, the needle holding portion having an open ended hole extending therethrough, whereby needles can be fed in from the end opposite to that from which they project when functioning the axis of the hole in said needle holder and a plane at right angles to the mean axis of the reproducer, through the point of contact between the reproducer and the stylus bar, both sub-

stantially intersecting the axis about which the stylus bar vibrates.

6. In a gramophone the combination of a reproducer, a stylus bar mounted for vibratory movement, said stylus bar having a needle holding portion, and a reproducer actuating portion, said actuating portion having a longitudinal passage, and a guide for directing the needle into the needle holding portion, said guide being formed as a blade like extension in one side of the channel, the needle holding portion having an open ended hole extending therethrough, whereby needles can be fed in from the end opposite to that from which they project when functioning the axis of the hole in said needle holder and a plane at right angles to the mean axis of the reproducer, through the point of contact between the reproducer and the stylus bar, both substantially intersecting the axis about which the stylus bar vibrates.

7. In a gramophone the combination of a reproducer, a stylus bar mounted for vibratory movement, said stylus bar having a needle holding portion, and a reproducer actuating portion, said actuating portion having a longitudinal passage, a tubular guide associated with the reproducer, the needle holding portion having an open ended hole extending therethrough, whereby needles can be fed in from the end opposite to that from which they project when functioning the axis of the hole in said needle holder and a plane at right angles to the mean axis of the reproducer, through the point of contact between the reproducer and the stylus bar, both substantially intersecting the axis about which the stylus bar vibrates.

8. In a gramophone the combination of a reproducer, a stylus bar mounted for vibratory movement, said stylus bar having a needle holding portion, and a reproducer actuating portion, said actuating portion having a longitudinal passage, said portions being disposed in out of line relationship, the needle holding portion having an open ended hole extending therethrough, a needle magazine mounted above and adjacent to said needle holder, said magazine having an outlet in line with the hole in said needle holder whereby needles can be fed in from the end opposite to that from which they project when functioning the axis of the hole in said needle holder and a plane at right angles to the mean axis of the reproducer, through the point of contact between the reproducer and the stylus bar, both substantially intersecting the axis about which the stylus bar vibrates.

9. In a gramophone the combination of a reproducer, a stylus bar mounted for vibratory movement, said stylus bar having a needle holding portion, and a reproducer

actuating portion, said portions being disposed in angular relationship, said actuating portion having a longitudinal passage and a guide for directing the needle into the
5 needle holding portion, the needle holding portion having an open ended hole extending therethrough, a needle magazine mounted above and adjacent to said needle holder, said magazine having an outlet in line with
10 the hole in said needle holder whereby needles can be fed in from the end opposite to that from which they project when functioning the axis of the hole in said needle holder and a plane at right angles to the
15 mean axis of the reproducer, through the point of contact between the reproducer and the stylus bar, both substantially intersecting the axis about which the stylus bar vibrates.

10. In a gramophone the combination of
20 a reproducer, a stylus bar mounted for vibratory movement, said stylus bar having a needle holding portion, and a reproducer actuating portion, said actuating portion being of channel section with the back of the
25 channel disposed towards the reproducer, said actuating portion having a longitudinal passage, and a guide for directing the needle into the needle holding portion, the needle holding portion having an open ended hole
30 extending therethrough, whereby needles can be fed in from the end opposite to that from which they project when functioning.

In witness whereof I affix my signature.
GEORGE BASIL KING.
